[57] **CLAIM**

The ornamental design for a fishing pole holding bucket, as shown.

DESCRIPTION

FIG. 1 is a perspective view of the fishing pole holding bucket in accordance with the present design;

FIG. 2 is a top plan view of the fishing pole holding bucket as shown in FIG. 1;

FIG. 3 is a front elevational view of the fishing pole holding bucket as shown in FIG. 1, (the opposite side of FIG. 1 is a mirror image of the view shown in FIG. 3);

FIG. 4 is a bottom plan view of the fishing pole holding bucket as shown in FIG. 1; and,

FIG. 5 is a right-side elevational view of the fishing pole holder as shown in FIG. 1.
